UNITED STATES PATENT OFFICE.

ABRAHAM G. HAMM AND ABRAHAM ABR. HAMM, OF ROSTHERN, SASKATCHEWAN,
CANADA.

HAIR-SPRING TESTER.

1,029,608.

Specification of Letters Patent. Patented June 18, 1912.

Application filed October 2, 1911. Serial No. 652,337.

To all whom it may concern:

Be it known that we, ABRAHAM GERHARD HAMM and ABRAHAM ABRAHAM HAMM, both subjects of the King of Great Britain, and 5 residing at Rosthern, in the Province of Saskatchewan, Canada, have invented certain new and useful Improvements in Hair-Spring Testers; and we do hereby declare that the following is a full, clear, and exact 10 description of the invention, such as will enable others skilled in the art to which it appertains to make and use the same.

The invention to be hereinafter described relates to hair spring testers.

15 In order to more clearly disclose the construction, operation, and use of the invention, reference should be had to the accompany drawings forming part of the present application.

20 Throughout the several figures of the drawings like reference characters designate the same parts.

In the drawings: Figure 1 is a side elevation of the invention, in use; Fig. 2 is a 25 top plan view of the same; Fig. 3 is a perspective view of one of the sinkers; Fig. 4 is a side elevation of a slight modification of the invention; and Fig. 5 is a perspective view of a second form of sinker, for very 30 delicate hair springs.

The main objects of the invention are to provide a simple, efficient, durable, and economical hair spring tester by which various sizes of hair springs may be quickly and 35 easily tested with absolute accuracy.

Referring to the drawings in detail, 1 indicates a suitable base from which extends a small crane 2 provided with one fixed jaw 3 and a coöperating pivotally mounted jaw 4. The jaw 4 is adapted to be held in operative position by means of a clamping screw 5. From each of the jaws projects a small ear 6. Between these ears is clamped the outer end of the spring to be tested. A 45 short distance from the crane and directly in front of its jaws, is a scale post or graduated rod 7 extending upwardly from the base 1. A sinker or weighted rod 8 is provided with a loop 9 on the end of an arm 10 which projects from the head of this rod.

The loop is adapted to slide freely on the rod or post 7 and to act as an index needle coöperating with the graduations on the rod. This rod 8 is of very small diameter 50 and adapted to slide freely through the in-

ner coil of the hair spring. It is provided with a conical hub 11 concentrically arranged about its upper end and adapted to engage the inner coils of the spring and stretch or extend the spring as the rod 60 moves downward. The hub, of course, acts, also, as a weight. The hub in Fig. 5 is smaller in diameter and substantially cylindrical.

In order to guide the rod and insure a 65 true vertical movement of it, a guide bar 12 has been provided. This guide bar is mounted to slide horizontally in the vertical post of the crane 2, so that its operated end may be adjusted into exact alinement with 70 the center of the hair spring which is held between the ears 6. This end is provided with two vertical bores 13 of different diameters. One diameter bore is adapted to slidably receive the lower end of the sinker 75 rod of Fig. 3 for testing hair springs ranging between certain gages, whereas, the other is adapted to similarly receive the lower end of the sinker of Fig. 5, for testing exceptionally delicate hair springs—more 80 particularly, Swiss hair springs. On reference to Figs. 4 and 5, it will be seen that the sinker for testing the very delicate springs is arranged with its loop 9 very close to its stem, requiring the graduated post to 85 be much nearer the crane. For this purpose, a second post 14 is, preferably, mounted slightly to one side of the line between post 7 and the crane end, and much closer to the crane end. It will be noticed that the 90 loop 9 of the sinker and the guide rod or bar 12 insure absolute and true vertical movement of the sinker. The loop will indicate by the graduations on the post 7, the exact strength of the hair spring, of course. 95

It is thought that the operation and use of the invention will be clear from the preceding detailed description.

Changes may be made in the construction, arrangement, and disposition of the several 100 parts of the invention without in any way departing from the field and scope of the same and it is meant to include all such within this application wherein only preferred forms have been disclosed.

Having thus fully described our invention, what we claim as new and desire to secure by Letters Patent is:

1. In combination, a crane for holding a hair spring, a graduated post adjacent to 110

said crane and independent thereof, and a sinker coöperating with said graduating post and adapted to engage said spring by the action of gravity.

5. 2. In combination, a crane for holding a hair spring, a graduated post adjacent to said crane, a sinker coöperating with said graduated post, and engaging said spring means for guiding the lower end of said 10 sinker and means carried by the upper end of said sinker and guiding it by engaging said post.

15. 3. A crane for holding a hair-spring comprising a fixed jaw and a movable jaw, said jaws being provided with contiguous ears, in combination with means for holding the said ears together on said spring, a graduated post adjacent to said crane, a sinker engaging said spring and a loop extending 20 from said sinker and coöperating with said graduated post.

4. In combination, a crane for holding a hair spring, a graduated post adjacent to said crane, a sinker engaging said spring, 25 and a loop extending from said sinker and coöperating with said graduated post.

5. In combination, a crane for holding a

hair spring, a graduated post adjacent to said crane, a sinker rod provided with a hub and engaging said spring, and a loop extending from said sinker rod and coöperating with said graduated post.

6. In combination, a crane for holding a hair spring, a graduated post adjacent to said crane, a sinker coöperating with said graduated post, and provided with a downwardly tapering enlarged conical part which enters said spring and bears thereon by gravity.

7. In combination, a crane for holding a hair spring, a graduated post adjacent to said crane, a sinker engaging said spring by gravity, a loop extending from said sinker and extending slidably about said post, and a guide bar mounted in said crane and 45 adapted to receive and guide said sinker.

In witness whereof we have hereunto set our hands in the presence of two witnesses.

ABRAHAM G. HAMM.
